Primary Examiner—Susan Moon Lee*(74) Attorney, Agent, or Firm*—Katten Muchin Rosenman LLP(57) **CLAIM**

I claim the ornamental design for a pet toy, as shown and described.

DESCRIPTION

FIG. 1 is a perspective view of a pet toy;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown do not form part of the claimed design.
